UNITED STATES PATENT OFFICE.

LLOYD V. LEWIS, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-CROSSING SIGNAL AND CONTROL THEREOF.

1,312,407.

Specification of Letters Patent. Patented Aug. 5, 1919.

Application filed August 21, 1916. Serial No. 115,926.

To all whom it may concern:

Be it known that I, LLOYD V. LEWIS, a citizen of the United States, residing at Edgewood Borough, in the county of Allegheny and State of Pennsylvania, have invented certain new and useful Improvements in Railway-Crossing Signals and Controls Thereof, of which the following is a specification.

10 My invention relates to warning signals for grade intersections of railways and highways, and the control thereof.

I shall describe one form of signal embodying my invention, and then point out 15 the novel features thereof in claims.

In the accompanying drawings, Figure 1 is a diagrammatic view showing one form 20 of warning signal embodying my invention and one means for controlling the signal, the signal being shown in the deenergized position. Fig. 2 is a diagrammatic view showing the warning signal shown in Fig. 1 in a position wherein it indicates safety, together with another form of apparatus and circuits 25 embodying my invention for the control of the signal. Fig. 3 is a view showing the ratchet device by which blades 23 are attached to motor shaft 24.

Similar reference characters refer to similar parts in each of the views.

30 Referring first to Figs. 1 and 2, the warning signal here shown comprises a pendulum P having at its lower end a disk 5. The signal is located adjacent the grade intersection 35 of a highway H and a railway track T, the location of the signal being preferably such that the pendulum P hangs over the middle of the highway so that it is plainly visible by pedestrians or occupants of vehicles using 40 the highway. The pendulum P is the warning member of the signal, which pendulum when oscillating about the vertical position shown in Fig. 1, indicates danger and when held in the horizontal position shown in Fig. 45 2, indicates safety. The pendulum is biased by gravity to hang vertically as shown in Fig. 1, and when in this position (in case of derangement of the apparatus or failure of the power supply, as I shall describe herein- 50 after), it gives a warning indication, distinctive from the aforementioned danger indication.

For operating the pendulum I provide an induction motor M comprising windings 1 and 2, which motor may at times be operated 55 by current supplied to one winding only, as I shall point out hereinafter. The rotor of motor M is connected through reduction gearing 3 with a segmental gear 4 to which is fixed the arm of pendulum P. As thus 60 far described, it follows that when motor M rotates in one direction or the other, the pendulum P swings in one direction or the other.

The force of gravity biasing the pendulum 65 to the vertical position, may be augmented at times by means of a helical spring 7. The upper end of this spring is secured to a member 8 which is attached to the pendulum arm by a pin 8^a, and the lower end of the 70 spring is secured to a similar member 11 which is connected by a pin 11^a to a bar 9, so that the spring is held far enough in front of the pendulum arm to permit the pendulum to swing behind the spring. 75 When the pendulum swings in either direction from the vertical position and bar 9 is held in the position shown in Fig. 1, spring 7 is stretched because the lower end of the 80 spring is fixed, whereas the upper end of the spring moves with the pendulum arm. Thus the spring biases the pendulum to the vertical position as long as bar 9 is held in fixed position. Bar 9 is pivotally mounted at 9^a, and may be latched in the position 85 shown in Fig. 1 by a latching pawl 10 pivoted on a fixed pin 10^a, which pawl is controlled by the armature 11 of a magnet 12 in such manner that when the magnet is de-energized the free end of the pawl 10 over- 90 hangs the free end of bar 9. The spring 7 pulls upwardly on bar 9 during each swing of the pendulum so that the free end of the bar engages the pawl when the pendulum swings in either direction from the vertical, 95 the normal length of the spring being such that when the pendulum hangs vertically, the free end of bar 9 is a small distance below the lower end of pawl 10, as shown in Fig. 1. When magnet 12 is energized, the 100 pawl 10 is turned to the right so that the bar 9 when pulled by spring 7 is free to turn upwardly, so that spring 7 is not stretched when the pendulum swings away from the

vertical position and is therefore unable to exert a biasing force on the pendulum. Fig. 2 shows how bar 9 is lifted upwardly by spring 7 when the pendulum is in the horizontal position.

Retaining means are provided for holding the pendulum in the horizontal position, which retaining means may be of any suitable type. The means I have shown in the 10 drawing comprises blades 23 extending radially from a disk 25 (see Fig. 3) mounted to rotate freely on shaft 24 of motor M. Pawls 25^a on disk 25 are biased to engage a ratchet wheel 24^a fixed to motor shaft 24. A roller 15 22 mounted on the free end of a lever 21 actuated by the armature of an electromagnet 20 is brought into the path of springs 23, when the pendulum is in the safety position, shown in Fig. 2, preventing clockwise rotation 20 of the motor shaft so that the pendulum is caused to remain in the horizontal position. That is, the ratchet device is so arranged that the pendulum may swing in counter-clockwise direction without causing 25 rotation of disk 25, but that when the pendulum swings in the other direction the disk must move with it, whereby in the latter case if the roller 22 is in the path of the blades the pendulum is locked.

30 A relay R is provided for the control of motor M and magnets 12 and 20, which relay is responsive to the approach of railway cars or trains to the highway crossing. As shown in Fig. 1, relay R is controlled by the 35 track circuit of a section of track a—b adjacent the intersection of the highway and the railway, this control (well understood in the art) being such that relay R is energized or deenergized according as the section is 40 unoccupied or occupied.

Alternating current for operating the motor M and electromagnets 12 and 20 is furnished by a transformer N supplied from an alternator not shown on the drawing.

45 For a description of the operation of the signal I shall first assume that the section of track a—b is unoccupied so that relay R is energized, and that hand switch S is open as shown in Fig. 1 so that the motor M and 50 magnets 12 and 20 are deenergized, allowing pendulum P to hang in the vertical position because of its bias.

When switch S is closed, relay R remaining energized, the pendulum is moved to the 55 horizontal position by the motor M. The circuit for winding 2 of the motor is as follows: from transformer N, through switch S, wire 26, winding 2, wire 38, electromagnet 12, wire 32, contact 33^a, contact segment 60 33^b on gear 4, contact 33^c, wire 34, contact 35—36 of relay R, and wire 37 to transformer N. The current in this circuit energizes, therefore, not only winding 2, but also electromagnet 12, which magnet closes at 65 contact 28—31 the following circuit for motor

winding 1: from transformer N, through switch S, wire 26, winding 1, wire 27, contact 28—31 of magnet 12, wire 32, contact finger 33^a, segment 33^b, contact finger 33^c, wire 34, contact 35—36 of relay R, and wire 70 37 to transformer N. Because of the inductance of magnet 12 in series with winding 2, the current in winding 2 lags behind the current in winding 1, so that motor M has two-phase action and turns counterclockwise, moving pendulum P to the horizontal position shown in Fig. 2. This movement of the pendulum is not opposed by spring 7 because magnet 12, being energized, has withdrawn latch 10 from the path of bar 9. 80 Motor M and magnet 12 are deenergized by the disengagement of finger 33^a from segment 33^b just before the pendulum reaches the horizontal position, but the inertia of the moving parts is sufficient to carry the pendulum far enough to cause segment 33^b to close at contact 33^c the circuit for the holding magnet 20, which circuit is as follows: from transformer N, through switch S, wires 26 and 42, magnet 20, wire 43, contact 90 finger 33^a, segment 33^b, contact finger 33^c, wire 34, contact 35—36 of relay R, wire 37 to transformer N. The motor is at this time rotating counterclockwise, so that one of the blades 23 engages the left side of roller 95 22 when the electromagnet lifts the roller into the path of the blades, causing the ratchet to slip until the motor comes to a standstill and begins to turn in the opposite direction, due to the weight of the 100 pendulum. A third of a revolution of the motor brings another blade 23 into contact with the right side of roller 22, as shown in Fig. 2, whereupon the ratchet prevents further clockwise rotation of the motor, locking pendulum P in the safety position, as 105 shown in Fig. 2.

When the signal is in this position, if a train approaches the highway crossing in the direction of the arrow (Fig. 1) and enters section a—b, relay R is deenergized and opens at contact 35—36 the circuit for holding magnet 20, so that the roller 22 drops out of engagement with the blade 23 and permits the motor to be turned clockwise by the force of gravity acting on the pendulum P. The relay R has in the meanwhile closed at its back contact 39 the following circuit for winding 1 of motor M: from transformer N, through switch S, wire 110 26, winding 1 of motor M, wire 27, contact 28—29, wire 30, contact 39—36 of relay R and wire 37 to transformer N. Winding 2 remains deenergized. Motor M, therefore, has single-phase action, and exerts torque 115 in the direction in which it is rotated by the swing of the pendulum, as soon as the pendulum has accelerated it to the pick-up speed. As the pendulum passes the vertical position bar 9 is caught under the latching 120 125 130

finger 10 of the magnet 12 because this magnet is now deenergized so that spring 7 is stretched as the pendulum continues its swing toward the left. The motor now drives the pendulum against the force of gravity and the spring tension, both of which continue to increase until the motor is stalled in some position such as indicated by the dotted line *x* in Fig. 1. The biasing forces on the pendulum then drive the pendulum and the motor in the reverse direction. The motor is soon brought up to the pick-up speed and again exerts its torque in the direction in which it has been started, until it is again stalled in similar manner when the pendulum reaches a position such as *y*. In this manner the pendulum *P* is caused to swing back and forth from *x* to *y* to give the danger indication while there is a car or train in section *a*—*b*.

When the car or train passes off this section, relay *R* is reenergized, opening the last-mentioned circuit for winding 1, and closing the circuits hereinbefore described for magnet 12 and both windings of motor *M*. The pendulum is then driven to and held in the horizontal position, as hereinbefore explained, so that the signal again gives the safety indication.

In case of failure of the power supply for transformer *N* or in case of derangement of some portions of the apparatus, the pendulum falls to the vertical position due to its bias, and remains there, no matter whether or not a train is approaching the crossing. The pendulum hanging vertically is a danger indication, separate and distinct from the warning given by the pendulum when oscillating, and serves to inform users of the highway that the signal is out of order, and to caution such persons to ascertain for themselves whether or not a train is approaching.

Referring now to Fig. 2, the signal controlling apparatus here shown comprises a track treadle 50 located a distance in the rear of the crossing. This treadle is adapted to be operated by the wheel flanges of a passing car or train, and governs a contact 51 which controls the circuit of relay *R*, as I shall describe hereinafter. A cam 52 is caused to oscillate with pendulum *P*, being fixed to the pivotal shaft thereof, as indicated diagrammatically by a dotted line. Springs 53 and 54 are biased to follow the cam surface, the former of these constituting part of a contact 55 and the latter one operating a ratchet wheel 56. The shape of cam 52 is such that at the end of each swing of the pendulum from right to left, contact spring 53 engages contact 55 and each swing of the pendulum in the reverse direction advances ratchet 56 one tooth. A cam 58 is fixed to ratchet wheel 56 and controls a con-

tact 57—59 in such manner that this contact is open at all times except when the cam is in one particular position.

The relay *R* is controlled by the above-mentioned contacts and is provided with a pick-up and a holding circuit. The pick-up circuit is from a battery 60, through wire 61, relay *R*, wire 62, contact 53—55, wire 63, contact 59—57, wires 64 and 65, contact 51, to battery 60. The holding circuit of relay *R* is as follows: from battery 60, through wire 61, relay *R*, wire 66, contact 67, wire 65, contact 51, to battery 60. From these circuits it is apparent that for the energization of relay *R*, both of the cam-controlled contacts on the signal must be closed as well as the treadle controlled contact 51, whereas, once energized, this relay remains closed by current flowing through its own contact 67, until the holding circuit is broken by the opening of treadle contact 51.

For a description of the operation of the signal with the controlling apparatus shown in Fig. 2, I shall assume at the outset that relay *R* is energized by current in its holding circuit, so that the pendulum *P* is in the safety position as hereinbefore explained. When a train approaching the crossing operates treadle 50, contact 51 opens the holding circuit of relay *R*, whereupon this relay opens contact 35—36 and closes contact 36—39, so that the signal begins to oscillate as hereinbefore described, indicating thereby the approach of the train to the crossing. As soon as the train has passed the treadle 50, contact 51 closes but relay *R* remains deenergized because its pick-up circuit is open at the cam-controlled contacts 53—55 and 59—57. The former of these is closed at every swing of the pendulum to the left, but the latter remains open until the pendulum has oscillated a predetermined number of times, according to the number of teeth on ratchet wheel 56. After the said number of oscillations, the contact 57—59 closes, during a swing of the pendulum from left to right, and during the next reverse swing of the pendulum the contacts 53—55 closes the pick-up circuit of relay *R* a sufficient length of time to energize the relay. As hereinbefore explained, this causes the operation of the pendulum to the safety position, during which movement the ratchet 56 is advanced another tooth so that contact 57—59 is again opened. Relay *R* is now held closed through the holding circuit as hereinbefore explained, and the signal apparatus is again in the position assumed at the outset.

It will be noted that the pendulum is caused to oscillate for a definite length of time after a train passes treadle 50, and the distance of this treadle from the crossing and the number of teeth in the ratchet with each stroke of the pendulum should be rela-

tively so proportioned that for trains of average speed the danger indication continues until the train reaches the crossing.

Although I have herein shown and described only one form of signal embodying my invention and certain arrangements of apparatus for the control thereof, it is understood that various changes and modifications may be made therein within the scope of the appended claims without departing from the spirit and scope of my invention.

Having thus described my invention, what I claim is:

15. 1. A railway crossing signal comprising a warning member mounted to oscillate and biased to an intermediate position, an induction motor capable of operation in either direction on current supplied to one winding only thereof, and means interposed between the rotor of said motor and said warning member for positively connecting the two, said parts being so proportioned that as said member approaches said intermediate position it causes the motor to rotate at pick-up speed and that the biasing force on said member overbalances the motor torque after the member passes said intermediate position whereby the operation is then reversed.
20. 2. A railway crossing signal comprising a member mounted to oscillate, and an induction motor operatively connected to said member, said motor comprising two windings, one for maintaining oscillations of said member to give a danger indication, and the other for coacting with said first winding to move said member away from its middle position to give a safety indication.
25. 3. A railway crossing signal comprising a member mounted to oscillate, an induction motor having a plurality of windings for driving the member to a safety position, and means for energizing at times a single winding of said motor to maintain the oscillation of said member to indicate danger.
30. 4. A railway crossing signal comprising a member mounted to oscillate, single phase means for oscillating the member to indicate danger and polyphase means for actuating the member to a safety position.
35. 5. A railway crossing signal comprising a member mounted to oscillate, single phase means for oscillating the member to indicate danger and polyphase means for actuating the member to a safety position, and means for retaining said member in the safety position.
40. 6. A railway crossing signal comprising a member mounted to oscillate, and an induction motor operatively connected to said member, said motor comprising two windings, one for causing oscillation of said member to give a danger indication, and another for coacting with said first winding to drive said member to a safety position, and means for retaining said member in the safety position, said means comprising a latch and an electromagnet for operating said latch.
45. 7. A railway crossing signal, comprising a pivoted member adapted to indicate safety when in one position and to indicate danger when oscillating about another position, resilient means for limiting the angle of oscillation of said member about the last mentioned position, and means for at times rendering said resilient means ineffective in its control of said member in order to permit movement of said member to said safety position.
50. 8. A railway crossing signal comprising a pivoted member adapted to indicate safety when in one position and to indicate danger when oscillating about another position, resilient means for limiting the angle of oscillation of said member about the last-mentioned position, a latch for at times rendering said resilient means ineffective in its control of said member, and an electromagnet for controlling said latch.
55. 9. A railway crossing signal, comprising a pivoted member adapted to indicate safety when in one position and to indicate danger when oscillating about another position, resilient means for limiting the angle of oscillation of said member about the last-mentioned position, a motor for driving said member beyond said limited angle of oscillation to the safety position, electromagnetic means for rendering when energized said resilient means ineffective in its control of said member, electromagnetic means for retaining when energized said member in the safety position, and circuits controlled by said member for deenergizing said motor and said first-mentioned electromagnetic means and for energizing said retaining means when said member reaches the safety position.
60. 10. A railway crossing signal comprising a member mounted to oscillate, single phase means for oscillating the member about one position to indicate danger, resilient means for limiting such oscillation to a given angle, polyphase means for actuating the member beyond said angle of oscillation to the safety position, electromagnetic means for rendering said resilient means inoperative in its control of the member, and electromagnetic means for retaining said member in the safety position.
65. 11. A railway crossing signal comprising a member mounted to oscillate, an induction motor operatively connected to said member, and comprising a single winding for oscillating said member about one position to indicate danger and a plurality of windings for driving said member to another position to indicate safety, resilient means for biasing said member to said first-mentioned position.

- sition, a latch for rendering said resilient means ineffective to bias said member, an electromagnet for controlling said latch, and means for holding said member in the safety 5 position.
12. In a railway crossing signal, an induction motor having two windings, a member biased to a central position and operatively connected with the rotor of said motor, and 10 means for at times energizing one winding and at other times both windings of said motor.
13. A signal comprising an induction motor having two stator windings, a member mounted to oscillate and biased to a middle position and operatively connected with the rotor of said motor, means for energizing both windings of said motor to move said member away from its middle position, 15 and means for energizing one winding only to cause said member to oscillate.
14. A railway crossing signal comprising a member mounted to oscillate and biased to an intermediate position by gravity, normally active mechanical means for increasing the force biasing said member to said position, an induction motor having two stator windings and having a rotor operatively connected with said member, and 20 means for at times energizing only one winding of said motor and for at other times energizing both windings of said motor and rendering said mechanical means inactive.
15. A railway crossing signal comprising an induction motor having two stator windings, a member mounted to oscillate and operatively connected with the rotor of said motor, a source of alternating current, two 25
- relays 12 and R; a circuit for one motor winding including said source, the winding 40 of relay 12 and a front contact of relay R; a circuit for the other motor winding including a front contact of relay 12 and a front contact of relay R and said source, and a branch for said latter circuit around 45 the said relay contacts and including a back contact of relay 12 and a back contact of relay R.
16. A railway crossing signal comprising a member mounted to oscillate and biased 50 by gravity to an intermediate position, mechanical means for increasing the force biasing said member to said position, an induction motor having two stator windings and the rotor of said motor being operatively 55 connected with said member, a source of alternating current and two relays R and 12; a circuit for one motor winding including said source, the winding of relay 12 and a front contact of relay R; a circuit for 60 the other motor winding including a front contact of relay 12 and a front contact of relay R, a branch for said latter circuit around said relay contacts and including a back contact of relay 12 and a back contact of relay R, and means controlled by the armature of relay 12 for rendering said 65 mechanical means operative or inoperative according as the relay is deenergized or energized.
